6 Claims. (Cl. 62—148)

1

This invention relates to cooling devices for liquids and particularly to improvements in the cooling means for beverage dispensers wherein the beverage is cooled while passing through tubes, coils or a cooling plate from which heat is absorbed by a cooling medium.

The main objects of this invention are to provide an improved cooling system for chilling beverage liquids; to provide an improved means for cooling liquids passing through a dispensing apparatus; to provide an improved combination of heat absorption means and heat transfer means for dispensers of liquids; to provide an improved means for utilizing a replaceable, self-contained refrigerant block for the direct cooling of cooling coils and plates in dispensing apparatus for liquids; and to provide an improved method of refrigerating cooling coils or plates by means of a unitary block type of refrigerant, which is normally at a temperature considerably lower than the desired temperature in the liquid being cooled, and for controlling the rate of heat flow from the cooling coils to the refrigerant block.

A specific embodiment of this invention is shown in the accompanying drawings in which:

Figure 1 is a perspective view of a beverage dispenser, of a type in general use at the present time, showing an application of the invention and illustrating a typical use thereof, the dispenser housing being partly broken away to show the principal elements of the invention.

Fig. 2 is a perspective view of a refrigerant block or unit such as may be used in the practice of the invention, the shell or body of the block being broken away to show its construction.

Fig. 3 is a diagrammatic view showing the relationship of the dispenser elements and the refrigerant block in a typical application of the invention.

Fig. 4 is a partial elevational view in section, illustrating the invention as applied to a dispenser of the type shown in Fig. 1.

Fig. 5 is a perspective view showing a cooling plate adapted for use in the practice of the invention.

Fig. 6 is a perspective view of a cooling coil construction adapted for use in practicing the invention, and

Fig. 7 is a perspective view showing one form of an independent spacer element used to space the refrigerant block from the cooling conduit.

The primary purpose of the present invention is to provide a simple and yet adequate refrigerating means for beverage dispensers and

the like which will eliminate the inconveniences accompanying the use of cracked or chipped natural ice without resorting to the expense and space requirements of a mechanical refrigerating apparatus.

In such cases the cooling problem, which the present invention solves, arises from the fact that the carbonated water, from which the drink or beverage is made, usually enters the dispenser at a temperature varying from 36° F. to 60° F., with an average of 47° F. to 50° F., and must be cooled to such an extent and at such a rate that, when mixed with the flavoring syrup for the drink, the drink will be delivered at a temperature less than 40° F. regardless of the frequency at which successive drinks are drawn. The syrup temperature usually averages about 50° F. and to maintain a drawn mixed drink temperature of less than 40° F. the cooling coils or cooling plate, through which the water passes, must be maintained at the lowest temperature which will not cause the water to freeze during a standing period when no drinks are being dispensed from the device. Thus, the coil or plate temperature must not go below about 31° F. and, to be practical, the cooling medium, or means, must be one that will hold the desired temperature over a considerable period of time without attention, and at the same time have sufficient reserve capacity to maintain the desired temperature under a sudden or extraordinary load.

In the practice of my invention I employ a hermetically sealed cold block or unit, which can be cooled to a very low temperature, as a cooling means or refrigerant and this cold block is used as a heat absorption means in place of the usual cracked or broken ice. Such a cold block or refrigerant unit is removed from the dispenser when warmed and replaced by another cold block and the warmed block is then refrozen by mechanical means, such as a deep freeze cabinet or an ice cream storage cabinet, which has a normal temperature of about 0 F. or less.

The use of such independent and renewable cold blocks as a cooling or refrigerating means is not of itself new, several types and constructions of these devices having been heretofore proposed for cooling purposes where there was an advantage to be gained over the use of ordinary ice. In the present instance, however, I employ, as an element of my invention, a cold block that is particularly designed to be cooled to a very low temperature and to hold a temperature well below the freezing point of water for a long period of time.

One form of such a cold block is illustrated in Fig. 2 and as shown comprises a hollow, generally rectangular body or container 1, made of sheet metal or any other suitable material, which contains a suitable solution 2 having a freezing point somewhat less than that of water. As indicated the solution does not fill the container, an air space of suitable size being left to accommodate expansion of the solution upon freezing, so that the container will not buckle or burst. For this purpose the container is initially made with two openings at one of its upper corners, the opening 3 in the top wall being a filling aperture and the opening 4 in a side wall being provided as a limit point for the filling operation. Thus the container is filled with the solution, through the opening 3, until the liquid begins to pour out of the opening 4 and then both openings are suitably sealed, the proper air space remaining in the container being determined by the location of the opening 4.

Several suitable solutions or freezing substances for this purpose are known in the art and for cooling the coils in a beverage dispenser I prefer a solution which will have a freezing point of about 25° F. and a relatively high heat of fusion. In practice I cool the cold block or refrigerant, containing this solution, to a temperature of about 7° to 15° F. and use the block unit, so cooled, as a substitute for ice. Such a cold block, when used as the refrigerant in a dispenser, will have a relatively slow temperature rise, compared with natural ice, and the time-temperature curve for the block will be almost flat for a period of from 6 to 8 hours depending upon the dispenser operating conditions and construction. Thus, at most, the block unit need be renewed or changed only twice a day and each block as it is used may be readily re-cooled by placing it overnight in a deep freeze cabinet or an ice cream storage chest which is refrigerated by mechanical means.

The danger and difficulty arising from the use of such a cold block, however, resides from the fact that the liquid to be cooled in the dispenser, usually carbonated water, has a freezing point considerably above that of the cold block when it is frozen and the cooling coil or plate of the dispenser is apt to become frozen if there is any substantial period during which the liquid is not flowing or drinks are not being drawn. To overcome this difficulty I employ a buffer between the cold block and the dispenser coil or plate, which functions as an insulator to reduce the heat transfer rate and relieve the cold shock that would otherwise be imparted to the coil or plate by the cold block when it is initially placed in the dispenser. Thus, my invention comprises the use of, and the means for providing, such a buffer in connection with the use of a cold block as a dispenser refrigerant.

In the form shown in the drawings the dispenser comprises a box-like body 5 having a top opening and a removable cover 6 therefor, the body and cover having hollow walls which are packed with a suitable insulating material. The body 5 is usually mounted, in upright position, on a pedestal 7, adapted to be secured to a counter 8 or other supporting means, and a step or shelf 9 is provided on the pedestal to support a glass or other drink receptacle below a discharge spout 10 which leads from the interior of the dispenser, as will be described.

Within the dispenser, and at the forward part thereof, is a syrup container 11, having a re-

movable cover for filling and cleaning purposes, and below the syrup container is a mixing valve 12 which is operated by a handle or lever 13 disposed on the outside of the dispenser body and suitably connected therethrough to the valve. Immediately behind the syrup container is a relatively large space 14 for housing the dispenser refrigerant and at the bottom of the refrigerant space or compartment is the coil or plate 15 which the refrigerant is to cool. As shown, the cooling coil is formed within a solid plate of aluminum, or other suitable material, and comprises an enclosed tortuous conduit 16 through which the carbonated water flows before being delivered to the mixing valve 12 for mixture with syrup and delivery to the discharge spout 10, the conduit having one end connected to a source of carbonated water supply and the other end suitably connected to the mixing valve, and the conduit path lying substantially in a common horizontal plane. This system is well known in the art and is illustrated diagrammatically in Fig. 3, excepting only that in the figure I show a cold block instead of natural ice.

As shown in Figs. 1 and 4, I provide a pan 17, at the bottom of the refrigerant compartment 14, which is of substantially the same area as, and lies directly upon, the cooling plate 15. This pan has a vertical wall 18 which extends continuously around its periphery and its inside dimensions are somewhat larger than the outside dimensions of the cold block 1 so that when the cold block is placed in the compartment 14 it can rest upon the pan with its sides spaced from the wall 18 all around. Also, the pan 17 is provided with a plurality of integral spacers or projections 19, extending upwardly from its bottom surface, on which the cold block 1 is supported in substantially uniformly spaced relation with the bottom of the pan. The spacers 19 are preferably located adjacent the four corners and the center of the pan 17 and the cold block thus has a minimum of metal-to-metal contact with the pan and a minimum path for the direct conduction of heat from the cold plate 15, through metallic contact.

The spacers 19 are of less height than the pan side walls 18 so that the pan wall will overlap the sides of the cold block 1, as shown in Fig. 4, and before the cold block is set into the pan, the pan is filled with water to completely cover the spacers. Then when the cold block is placed in the pan, the water is displaced upwardly around the sides of the cold block and contact of the entire bottom surface of the cold block with the water is assured.

This static body of water serves initially as an insulator between the cold block and the cooling coil and, because of the low initial temperature of the cold block, soon freezes to form a layer or wall of ice of substantially uniform thickness between the cold block and the cooling coil which, through surface contact with both the cold block and pan, is in heat conducting relation with both. During the freezing process the water absorbs the initial shock of the relatively large cooling capacity of the cold block and, because of its relatively low rate of heat conduction, compared to that of the materials from which the cooling coil and cold block unit are made, the water and ice function as a wall or buffer to retard the rate of heat transfer from the cooling coil to the cold block and thus protects the coil. Also, freezing the water and ice absorbs and thus accumulates or stores a very large cooling

potential between the cold block and the coil so that heat exchange between the two thereafter occurs at a self-controlled rate, the accumulated cooling potential residing in the high heat of fusion absorbed from the water in producing the ice.

In practice, the wall or sheet of ice melts slightly on the side adjacent the coil whenever liquid is drawn from the coil, due to heat being absorbed from the liquid entering the coil to be cooled, and the extent or amount of such melting varies according to the rate at which liquid flows through the coil. The direct action of the cooling block, however, is to absorb the heat from the melted ice and to refreeze it.

This is accomplished very rapidly through the agency of the metal spacers 19, which are in heat conducting relation with both the coil and the cold block and thus provide a ready path for direct heat flow to the cold block from the area adjacent the coil where the melting occurs. The area of contact of the spacers with the cold blocks, however, is kept to a minimum or relatively small amount because the principal heat conducting function of the spacers is solely to refreeze the melted ice adjacent the cooling coil and the rate of heat conduction must not be such as to cause freezing of the liquid within the cooling coil. Rather the spacers 19 serve for quick freezing of the melted ice only and the ice layer, with its relatively slow uniform heat conductivity, serves as the principal means for keeping the coil and its contents at the desired temperature. Therefore, the area of heat conducting contact between the spacers and the cold block should be determined according to the average of flow of fluid through the coil in order to prevent any accumulation of melted ice next to the coil, and the number of spacers used may be increased or decreased proportionately to the average rate of fluid flow through the coil to accomplish this result. Melted ice adjacent the coil is objectionable since water is a slow heat conductor and its presence would prevent the ice layer between the cold block and the coil from performing its function of keeping the entire coil at the necessary average temperature for proper cooling of the fluid dispensed from the cooler. Thus it is the accumulated cooling capacity or potential of the ice that serves principally to cool the liquid flowing through the coil and although there is heat conduction through the spacers to the cold block, the ice layer also protects the coil from freezing. When there is no flow through the cooling coil the ice wall or layer then functions as an insulator and buffer to retard the rate of heat transfer sufficiently to prevent freezing of the coil, even though the liquid in the coil might stand for some time and even though there is some heat flow through the spacers 19.

In this last respect, and because the thickness of the ice layer or sheet determines the rate of normal heat flow from the cooling coil or cold plate, it is often desirable to be able to vary the thickness of the ice layer or buffer according to normal operation rate of the cooler. That is, according to the average rate at which a particular dispenser is used to deliver cooled fluid for drinks. In such cases I provide interchangeable spacers 20, which may be of the type illustrated in Fig. 7, instead of the integral bosses formed in the pan bottom. These spacers may be furnished in different heights, such as $\frac{1}{8}$ ", $\frac{1}{4}$ " and $\frac{3}{8}$ ", and in use are merely set in place on the pan 17 before the cold block is installed. Thus where

the service is heavy and drinks are rapidly drawn the ice layer may be made thin by using the shortest spacers; and where the service is light and drinks are drawn infrequently the ice sheet or wall may be made thicker by merely using a spacer of greater height, the thickness of the ice layer or wall in any event being substantially the same as the length of the spacers used and determining the heat conduction rate and the cooling potential accumulation effect between the cooling coil and the cold block or refrigerant unit.

A modified form of the cooling plate arrangement for practicing my invention is shown in Fig. 5 wherein the plate 21, having an internal conduit 22, is formed with an integral marginal flange 23, projecting upwardly from the upper plate surface, to provide a receptacle or retainer for the body of water which forms the ice buffer between the cooling plate and the cold block. In this instance the replaceable spacers 20 are used to determine the ice sheet thickness or the space between the mutually facing surfaces of the cooling plate and the cold block unit.

Another form for the cooling plate is shown in Fig. 6, and in this arrangement the plate is made from two pieces of stamped sheet metal 24 and 25 which are formed to provide the water enclosed conduit 26 between them. These sheets are suitably secured together, as by welding, and the upper sheet 24 is provided with a peripheral flange 27 to provide a water retaining wall. In this case the spacers 20 are positioned in the flat areas between the conduit walls and must, therefore, be taller than the height of the uppermost surface of the conduit in order that the layer of ice formed between the adjacent mutually facing surfaces of the cold block and conduit wall have the desired thickness.

It should be understood that this invention is applicable to many forms and constructions of dispensers, some of which have the cold plate formed as a unit with the syrup container for easy removal and cleaning, and others in which the cooling coil may be merely of tubing laid in courses in the refrigerant chamber. In any case the particular construction of the dispenser itself, apart from the cooling system herein disclosed, is not a part of the present invention.

It should also be understood that other means than that herein shown and described may be utilized to space the cold block from the cooling coil and to provide an ice wall of predetermined thickness in heat conducting relation with them. Also the material which provides the buffer wall may be other than water and of any suitable composition which will provide the desired insulating and accumulator effect.

The main advantages of this invention reside in the ease and convenience of operation resulting from the use of a cold block or unit as a refrigerant in place of natural ice; and in the cleanliness of the interior of the dispenser that is obtained by eliminating the use of natural ice. Other important advantages reside in the means by which a cold block, cooled considerably below the freezing point of the liquid to be chilled, may be utilized without danger of freezing the cooling coil or plate through which the liquid is conducted.

Still further advantages are to be found in the simple arrangement for varying the buffer effect of the ice layer between the cooling conduit and the refrigerant block whereby the system may be made to accommodate the particular average

conditions of dispenser operation in any installation; and in the fact that a 'cold block' used in accordance with the invention has a cooling capacity capable of efficient use over a long period to hold the temperature of the liquid delivered by the dispenser at the desired level regardless of the delivery rate.

Although several specific embodiments of this invention are herein shown and described it will be understood that details of the construction shown may be altered or omitted without departing from the spirit of the invention as defined by the following claims.

I claim:

1. A cooling system for liquids comprising a conduit providing a tortuous path for the liquid to be cooled, which path lies wholly within a common plane, a refrigerant disposed adjacent said conduit and consisting of an independent sealed container having a frozen substance therein which substance is a liquid at normal room temperature and has a freezing point below that of the liquid to be cooled, said container having a wall surface lying substantially parallel with the plane of said conduit, a solid frozen heat conducting buffer disposed between said conduit and the refrigerant container and in direct contact with each over their mutually facing surfaces, said buffer having a lower heat conductivity than said conduit and said container, and spaced heat conducting elements having higher heat conductivity than said buffer extending through said buffer between the conduit and said container and in heat conducting relation with each.

2. A cooling system for liquids comprising a conduit for the liquid to be cooled, a refrigerant disposed adjacent said conduit and consisting of an independent sealed container having a frozen substance therein which substance has a freezing point below that of the liquid to be cooled, a solid heat conducting buffer of substantially uniform thickness disposed between said conduit and the refrigerant container and in direct contact with each over their mutually facing surfaces, said buffer being normally a liquid having a freezing point above that of the liquid to be cooled and a lower heat conductivity than said conduit and said container when frozen, and spaced heat conducting elements having higher heat conductivity than said buffer extending through said buffer between said conduit and said container and in heat conducting relation with each.

3. A cooling system for liquids comprising a conduit means lying substantially within a common horizontal plane and adapted to provide an enclosed tortuous path for the liquid to be cooled, a unit refrigerant positioned above and adjacent said conduit means and consisting of a sealed hollow body having a substantially flat bottom surface extending parallel with the plane of said conduit means, said body containing a frozen

substance having a freezing point below that of water, a buffer comprising a layer of solid ice disposed between said refrigerant body and said conduit means and normally in contact with the mutually facing surfaces of both, and a plurality of spaced heat conducting elements extending from said conduit means to said refrigerant body through said layer of ice and in heat conducting relation with each.

4. A cooler for liquids comprising a conduit means adapted to provide an enclosed path for the liquid to be cooled, a unit refrigerant consisting of an independent sealed hollow body containing a frozen substance having a freezing point below that of water, said refrigerant body being disposed adjacent said conduit means in substantially uniformly spaced relation therewith, means to retain a wall of water between said refrigerant body and said conduit means and in heat conducting relation with each, and a plurality of spaced heat conducting elements extending from said conduit means to said refrigerant body through said wall of water, said wall of water being normally frozen solid to said conduit means by contact with said refrigerant body, and said elements having a higher heat conductivity than the frozen wall of water.

5. In a cooler for liquid having a horizontally disposed conduit means adapted to provide an enclosed tortuous path for the liquid to be cooled, means on the upper side of said conduit means adapted to retain a static layer of water of predetermined depth thereon, and a plurality of heat conducting spacer elements projecting upwardly from said conduit means for directly contacting and supporting an independent self-contained refrigerant unit in heat conducting relation with and at a predetermined distance above said conduit means and in surface contact with the static body of water.

6. The combination with a cooler for liquids having a horizontally disposed conduit means adapted to provide an enclosed tortuous path for the liquid to be cooled, of means on and in heat conducting relation with said conduit means adapted to retain a static layer of water on the upper side thereof, and a plurality of heat conducting spacer elements in contact with and projecting upwardly from the last named means for directly engaging and supporting an independent self-contained refrigerant unit at a predetermined distance above said conduit means and in surface contact with the static layer of water.
